DESIGN FOR A RADIATOR CAP

Lester K. Franklin, Chicago, Ill.

Application December 1, 1933. Serial No. 49,901

Term of patent 7 years

To all whom it may concern:

Be it known that I, LESTER K. FRANKLIN, a citizen of the United States, residing at Chicago, in the county of Cook and State of Illinois, have invented a new, original, and ornamental Design for a Radiator Cap, of which the following is a specification, reference being had to the accompanying drawing, forming part thereof,

Figure 1 is a side elevation of a radiator cap showing my new design; and
Figure 2 is a plan view of the same.

I claim:

The ornamental design for a radiator cap, substantially as shown.

LESTER K. FRANKLIN,
